(21) Appl. No.: **29/128,912**

(74) Attorney, Agent, or Firm—Rosenberg, Klein & Lee

(22) Filed: **Sep. 6, 2000**

CLAIM

(51) LOC (7) Cl. **24-04**

The ornamental design for a transcutaneous electrical nerve stimulation device, as shown and described.

(52) U.S. Cl. **D24/200**

DESCRIPTION

(58) Field of Search D24/200; 607/41,

FIG. 1 is the perspective view of a transcutaneous electrical nerve stimulation device showing my new design;

607/45-46, 48, 50, 54-56, 58, 66, 72; 600/544,
546

FIG. 2 is the front view thereof;

(56) **References Cited**

FIG. 3 is the rear view thereof;

U.S. PATENT DOCUMENTS

FIG. 4 is the left side view thereof;

D. 383,212 * 9/1997 Okabe D24/200
D. 411,887 * 7/1999 Agarwala D24/200

FIG. 5 is the right side view thereof;

FIG. 6 is the top view thereof; and,

FIG. 7 is the bottom view thereof.
